UNITED STATES PATENT OFFICE

2,071,873

SIGNALING APPARATUS

Louis E. Dierks and Charles E. Severson, Oak Park, Ill.

Application January 2, 1935, Serial No. 158

12 Claims. (Cl. 116—39)

Our invention relates more particularly to apparatus carried by automobiles for signaling to approaching automobiles the direction in which the drivers of the automobiles in advance, intend to turn; and our objects, generally stated, are to provide a novel, simple and positively operating construction of such apparatus; to provide means whereby the operator of the signaling apparatus may be apprized as to whether or not the apparatus is properly functioning without viewing the signaling means; and other objects as will be manifest from the following description.

Referring to the accompanying drawings:

Figure 1 is a view in longitudinal sectional elevation of the signaling arm of our improved signaling apparatus and its associated operating mechanism, the arm being shown by full lines in the position to indicate a left turn and by dotted lines in the position to indicate a right turn.

Figure 2 is a section taken at the irregular line 2 on Fig. 1 and viewed in the direction of the arrow, the signaling arm being shown in normal, depending, non-signaling, position.

Figure 3 is a view in side elevation of the upper end of the steering wheel mechanism of an automobile shown as equipped with valve mechanism forming a part of the signaling apparatus and through the medium of which the position of the signaling arm is controlled.

Figure 4 is a diagrammatic view of electrical mechanism controlled through the medium of the valve of Fig. 3 for indicating to the driver of the car whether or not the signaling apparatus is properly functioning.

Figure 5 is an enlarged view in longitudinal sectional elevation of a duplex piston and cylinder mechanism by which the signaling arm may be operated into the desired signaling position.

Figure 6 is a broken section taken at the line 6 on Fig. 5 and viewed in the direction of the arrow.

Figure 7 is an end view of the valve mechanism of Fig. 3, the mechanism being viewed from the right in this figure.

Figure 8 is a plan view, partly sectioned, of the valve device of Fig. 7.

Figs. 9, 10 and 11 are broken sections taken at the lines 9, 10 and 11, respectively, on Fig. 8 and viewed in the direction of the arrows.

Figure 12 is an enlarged broken view in vertical sectional elevation taken through the upper portion of the structure shown in Figs. 1 and 2, the section being taken at the line 12 on Fig. 1 and viewed in the direction of the arrow.

Figure 13 is an enlarged view in longitudinal

sectional elevation of another form of piston and cylinder mechanism which may be utilized for actuating the signaling arm, the section being taken at the line 13 on Fig. 14 and viewed in the direction of the arrow.

Figure 14 is a section taken at the line 14 on Fig. 13 and viewed in the direction of the arrow; and

Figure 15, an enlarged view in sectional elevation of one of the similar check valves in the upper piston head and in the bottom of the cylinder of the construction of Figs. 13 and 14.

Referring to the construction shown in Figs. 1-12, inclusive, the apparatus comprises a casing 15 which in practice would be mounted on 15 the rear end of an automobile and on which casing a signaling arm 16 is pivoted at its upper end to be swung upwardly in either direction, under the control of the operator, from a position in which it depends (Fig. 1).

The arm 16, preferably of hollow construction as shown and presenting an arrow 17 in translucent material rendered luminous by an electric lamp 18, is rigidly secured to a hollow rock-shaft 19 journalled in a side wall 20 of 25 the casing 15, a bracket 21 in the casing and a hood 22 secured to the casing, the shaft 19 between the wall 20 and bracket 21 being square in cross-section and on which portion is mounted, to rotate with the shaft, a gear 23 and a switch- 30 operating collar 24.

The means for actuating the signaling arm 16 comprises a pair of racks 25 and 26 meshing with the gear 23 at its opposite sides and carried on the upper end of piston rods 27 and 28, respectively, having pistons 29 and 30, reciprocable in cylinders 31 and 32 mounted in the casing 15.

The cylinders 31 and 32 are provided at their lower ends with fittings 33 and 34 which open into the cylinders, respectively, and into pipes 35 and 36, respectively, adapted to be selectively connected, under the control of the operator, with a desirable source of suction; as for example, with the suction side of the engine of the automobile. The fitting 33 is also connected with a pipe 37 which opens into the upper end of the cylinder 32 and the fitting 34 with a pipe 38 which opens into the upper end of the cylinder 31, both of these cylinders being otherwise closed above the pistons therein.

The cylinders 31 and 32 contain vertical ports 39 and 40, respectively, in their bottom walls in which valves 41 and 42, respectively, are vertically movable. The valves 41 and 42 are pivoted at their lower ends at 43 and 44 on the ends of a 55

cross-bar 45 pivoted at 46 between its ends to a bracket 47 on a cross-bar 47^a connecting the cylinders together, the arrangement of these parts being such that both valves 41 and 42 may be open at the same time.

The pipes 35 and 36 lead to a valve mechanism 48 so located as to be readily accessible to the driver of the automobile, as for example and as shown, on the steering wheel 49 of the automobile. The valve device 48 comprises a casing 50 containing a tapered socket 51 in which a tapered hollow valve-proper 52 is rotatable as by means of the handle 53. The casing 50 has two ports 54 and 55 opening into the socket 51 at different points therealong and connected with the pipes 35 and 36, respectively. At the opposite side of the socket 51 is a port 56 which connects with a pipe 57 which would lead to any suitable source of suction. The valve 52 contains a port 58 adapted to remain in communication with the port 56 at all times and ports 59 and 60 disposed in angular relation to each other as shown and selectively movable into registration with the ports 54 and 55, respectively, the arrangement being such that the ports 59 and 60 are never at the same time in registration with the ports 54 and 55. Stops 61 and 62 in the path of movement of the lever 53 serve to ensure registration of the ports 59 and 60 with the ports 54 and 55 in the extreme rotary movements of the valve 52; flat-surfaces 63, 64 and 65 on the valve 52 in the plane of a projection 66 on a flat spring 67 secured to the valve casing 50 releasably hold the valve in any of its three positions of adjustment, against accidental displacement.

Means are provided for signaling to the operator as to whether the apparatus is functioning to swing the arm 16 to signaling position, these means comprising an electric lamp 68 shown as mounted on the valve mechanism 48, a relay-operated switch 69 for closing the circuit to the lamp 68 when the magnet coil 70 thereof is energized, and a switch 71 actuated by the shaft 19 for closing the circuit of the relay coil 70 to close the switch 69 and light the lamp 68 after the shaft 19 has started to turn.

The illustrated apparatus and circuit connections for thus controlling the lamp 68 (Fig. 4) showing a battery 72, by way of example as a source of current, are as follows:

The relay switch comprises an upper stationary contact 73 and a lower movable contact member 74 in the form of an armature shown as gravity operated to open position when the coil 70 is not energized, the member 74 being pivotally supported at 75.

The switch 71 comprises spring arms 76 and 77 supported on the casing 45 with interposed insulation 78, the arms being normally out of contact. The peripheral portion of the collar 24 which is in the plane of the arm 77 is partially cut away as represented to present a flat surface 79 with which the arm 77 registers, and thus is out of contact with arm 76, when the valve 52 is in normal position (Figs. 4 and 7-11). Rotation of the valve 52 toward either of its extreme positions closes the circuit at the switch 71.

One terminal of the battery 72 connects, by a wire 80 with the armature 74 and the other terminal with a wire 81 which connects with a wire 82 leading from the stationary contact 73 to the switch member 77, the lamp 68 and the lamp 18 being shown as interposed in this wire at opposite sides of the juncture of the wires 81 and 82. The

other member 76 of switch 71 connects by a wire 83 with one terminal of the coil 70 the other terminal of which connects, by a wire 84 with the wire 80. The portions of the wire 82 adjacent the lamp 18 are shown as extending into the casing 45 and through the hollow shaft 19 to the lamp 18 which is shown as depending therefrom.

Assuming the parts of the apparatus to be in normal position as shown in Figs. 2 to 12, inclusive, in which position the arm 16 hangs down vertically from its pivot shaft 19, the pistons 29 and 30 occupy the intermediate positions shown, the valves 39 and 40 are open, both cylinders 31 and 32 are out of communication with the source of suction and the switch 71 is open and both lamps 18 and 68 deenergized, the operator, assuming he wishes to signal a left turn, would turn the valve 52 in clockwise direction in Figs. 9-11 to bring the port 60 into registration with the port 55 whereupon suction would be exerted through pipes 57 and 36 in the lower end of the cylinder 32 and in the upper end of the cylinder 31 through the cross pipe 38. The first action of the suction thus applied would be to raise the valve 42 to close port 40 and lower the valve 41 to further open the port 39 and through the cross pipe 37 the upper end of the cylinder 32, to the atmosphere. The suction action in continuing will draw piston 30 downwardly and pull piston 29 upwardly thus actuating the gear 23 to swing the arm 16 upwardly to the left in Fig. 1 to the full line position therein shown. Upon the initial turning of the valve 52 to the position stated the contact 71 is flexed into engagement with the contact 76 which closes the circuit through the lamp 18 and solenoid 70 and by reason of the energizing of the latter closes the switch 69 and energizes lamp 68.

To restore the several parts to normal position the operator rotates the valve 52 back to normal position (Figs. 9-11) thus shutting off suction to the piston and cylinder mechanism, whereupon the valves 41 and 42 assume open position (Fig. 5) permitting the signaling arm 16 to swing to depending vertical position, the pistons 29 and 30 assuming the intermediate positions as shown in Fig. 5 and the switch 75 becoming open (Fig. 4) thus extinguishing the lamp 18 and by breaking the circuit through the coil 70 extinguishing the lamp 68.

The actuation of the signaling arm 16 to the dotted right-hand position shown in Fig. 1 is accomplished by the operator rotating the valve 52 in counterclockwise direction from the normal position shown in Figs. 8-10 to a position in which the port 59 registers with the port 54 which results in suction being exerted in the lower end of the cylinder 31 and the upper end of the cylinder 32 (the valve 41 automatically closing by the suction) and the opening of the upper end of the cylinder 31 and the lower end of the cylinder 32 to the atmosphere, the lamps 18 and 68 becoming energized in the initial movement of the valve 52 as explained above in connection with the description of the operation of the signaling arm 16 to indicate a left turn, the operated parts returning to normal position upon the rotation of the valve 52 by the operator back to normal position.

Certain features of the invention may also be embodied in mechanism for actuating the signaling arm 16 of a type involving a single piston and cylinder device (the piston being double acting), instead of the duplex piston and cylinder

mechanism of Figs. 1 to 12, inclusive. Figs. 13, 14 and 15 show such an embodiment of the invention, the single cylinder thereof, represented at 85, and located in the casing 15, being provided as a substitute for the cylinders of the construction of the preceding figures of the drawings. The cylinder 85 contains a double acting piston represented generally at 86 and comprising two piston head portions 87 and 88 connected together by a stem 89 having an arm 90 extending laterally through, and vertically slideable in, a slot 91 in a side of the cylinder, the outer end of the arm 90 being connected with an upwardly extending bar 92 having a rack portion 93 meshing with the gear 23 for actuating the latter responsive to the actuation of the piston device 86 in either direction, under the control of the operator, for causing the signaling arm 16 to be swung in either direction, from vertical depending position to substantially horizontal position for indicating the direction in which the vehicle is to turn, the bar 92 being shown as backed by a roller 94 journaled on the casing 15 to insure intermesh of the rack 93 with the gear 23 at all times.

The upper piston 87 and the bottom wall 95 of the cylinder 85 contain openings therethrough as represented at 96 of the bottom wall 95 of the cylinder and in which check valves 97 each of the same construction, are located. Each of the check valves 97 is shown as comprising a valve casing 98 adapted to be screwed into the opening to be controlled thereby, each casing containing a valve seat 99 with which cooperates a ball-check 100 which normally rests, in spaced relation to the seat 99, on a cross pin 101 carried by the casing, the balls 100 of the valve devices being adapted to be drawn into engagement with their seats upon the exertion of suction at the upper ends of the casings 98.

Any suitable valve mechanism, such as that shown in Figs. 7-11, may be provided for exerting suction selectively in the cylinder above the piston portion 87 and below the piston portion 88 to swing the signaling arm 16 in the desired direction, the suction being exerted in the upper end of the cylinder through the pipe 102 and in the lower end of the cylinder through the pipe 103, these two pipes, where the valve mechanism of Figs. 7-11 would be employed, being connected, respectively, with the ports 54 and 55.

It will be understood from the foregoing that in the normal position of the device the signaling arm 16 will hang vertically from its pivot shaft 19, the piston device 86 will assume the intermediate position shown in Figs. 13 and 14, and both of the check valves 97 will be open. Assuming that the signaling arm 16 is to be swung upwardly to the left in Fig. 13 to indicate a left-hand turn, the operator manipulates the valve 52 to exert suction in the cylinder 85 above the piston 87 which causes the check valve 97 in the piston 87 to close and the piston device 86 to be bodily raised and actuate the arm 16 as stated through the medium of the rack 93 and gear 23, the check valve 97 in the bottom of the cylinder 85 remaining open to equalize the pressure at opposite sides of the piston 88 and thereby not interfere with the lifting of the piston device by the suction action. The parts operated as described remain in the positions to which they are operated until the valve 52 is returned to normal position whereupon the check valve 97 in the piston portion 87 opens, and the signaling arm 16 thereupon swings back to normal depending position,

returning to the normal position shown in Fig. 13 the operating mechanism for the signaling arm. Movement of the signaling arm 16 from depending position, upwardly to the right in Fig. 13 to indicate a right-hand turn is effected by admitting suction to the cylinder 85 below the piston 88 which results in the automatic closing of the check valve 97 in the bottom of the cylinder to permit of the building up of negative pressure below the piston portion 88 to draw the piston 10 downwardly and thus swing the signaling arm 16 to the position stated, the check valve 97 in the piston portion 87, remaining open during this operation of the device. As soon as suction through the pipe 103 is discontinued the lower check valve 97 opens, whereupon the arm 16 swings back to normal depending position and the operating parts again assume the position shown in Fig. 13.

While we have illustrated and described certain forms of construction in which our invention is embodied, we do not wish to be understood as intending to limit it thereto as the same may be variously modified and altered and the invention embodied in other forms of structure without departing from the spirit of the invention.

What we claim as new and desire to secure by Letters Patent is:

1. Signaling means comprising a signaling device movable into different positions and automatically returnable to normal position, piston and cylinder mechanism for controlling the position of said device, means for actuating said mechanism and relief means embodied in said mechanism for automatically equalizing the pressure in said mechanism upon discontinuing the application of driving power thereto thereby to permit said signaling device and said mechanism to return to normal position.

2. Signaling means comprising a signaling device adapted to normally assume depending position and swingable in either direction therefrom, piston and cylinder mechanism for controlling the position of said device, means for actuating said mechanism and relief means embodied in said mechanism for automatically equalizing the pressure in said mechanism upon discontinuing the application of driving power thereto thereby to permit said signaling device and said mechanism to return to normal position.

3. Signaling means comprising a signaling device movable into different positions and automatically returnable to normal position, a pair of piston and cylinder devices for actuating said signaling device and operating in opposite directions, and means for exerting suction in one end of one cylinder and the opposite end of the other cylinder to move said signaling device into one position, and for exerting suction in the other ends of the cylinders to move said signaling device in the opposite direction.

4. Signaling means comprising a pivoted signaling arm, a gear rotatable with said arm, a pair of piston and cylinder devices having rack portions on the movable parts of said devices engaging said gear at opposite sides thereof, and means for actuating said devices for actuating said arm.

5. Signaling means comprising a signaling device movable to and from a neutral position to two different projected positions, a pair of piston and cylinder devices operatively connected with said signaling device and moving in opposite directions, means for exerting suction in said cylinders for moving said signaling device into

- said different positions, and valve means on said devices operating automatically to close said cylinders to the atmosphere when suction is applied thereto and open said cylinders to the atmosphere 5 when suction is discontinued.
6. Signaling means comprising a signaling device movable to and from a neutral position to two different projected positions, a pair of piston and cylinder devices operatively connected with 10 said signaling device and moving in opposite directions, means for exerting suction in said cylinders for moving said signaling device into said different positions, and valve means for said cylinders comprising valves operatively connected together to move in opposite directions, one to closed position and the other to open position, and operating automatically to close said cylinders to the atmosphere when suction is applied thereto and open said cylinders to the atmosphere 15 when suction is discontinued.
7. Signaling means comprising a signaling device movable into different positions and automatically returnable to normal position, piston and cylinder mechanism comprising a cylinder 20 and a double-acting double-headed piston therein for controlling the position of said device, means for actuating said mechanism, and relief valves in one of said heads and one end of said cylinder for automatically equalizing the pressure in said mechanism upon discontinuing the application of driving power thereto thereby to permit said signaling device and said mechanism to return to normal position.
8. Signaling means comprising a signaling device movable into different positions and automatically returnable to normal position, piston and cylinder mechanism comprising a double-acting double-headed piston therein, an arm connected with said piston and extending through, 25 and movable along, a side of said cylinder, said arm being operatively connected with the signaling device, means for actuating said piston, and relief valves in one of said heads and one end of said cylinder for automatically equalizing the pressure in said cylinder upon discontinuing the application of driving power thereto thereby to 30
- permit said signaling device and said piston to return to normal position.
9. Signaling means comprising a signaling device movable into different positions and automatically returnable to normal position and suction means for actuating said device comprising a pair of piston and cylinder devices operatively connected with said signaling device and moving in opposite directions and relief valves in said cylinders for automatically relieving back vacuum pressure which would otherwise be produced in the actuating of said signaling device. 35
10. Signaling means comprising a signaling device movable into different positions and automatically returnable to normal position and suction means for actuating said device comprising a pair of piston and cylinder devices operatively connected with said signaling device and moving in opposite directions and relief valves in said cylinders for automatically relieving back vacuum pressure in the portions of said cylinders other than those in which the operative suction is exerted when actuating said signaling device. 40
11. Signaling means comprising a signaling arm adapted to normally assume a perpendicular position and swingable in either direction therefrom; a pair of suction-operated means connected to, and each operable for swinging, said arm in a different direction from normal position, said means comprising pistons and cylinders, said cylinders containing ports, valves controlling said ports and means interconnecting said valves for movement in opposite directions. 45
12. Signaling means comprising a signaling arm adapted to normally assume a perpendicular position and swingable in either direction therefrom, a pair of suction-operated means connected to, and each operable for swinging, said arm in a different direction from normal position, said means comprising pistons and cylinders, the bottoms of said cylinders containing ports, valves controlling said ports, and a member pivotally supported between its ends and pivoted at opposite sides of its pivotal support to said valves. 50
